UNITED STATES PATENT OFFICE.

BARNARD S. BOZARD, OF BROOKLYN, NEW YORK.

SAW-JOINTER.

SPECIFICATION forming part of Letters Patent No. 298,820, dated May 20, 1884.

Application filed September 6, 1883. (No model.)

To all whom it may concern:

Be it known that I, BARNARD S. BOZARD, of the city of Brooklyn, in the county of Kings and State of New York, have invented 5 an Improved Saw-Jointer; and I hereby declare the following to be a full, clear, and exact description thereof, reference being had to the accompanying drawings, which form a part of this specification.

10 The object of this invention is to provide a cheap and convenient saw-jointer, or instrument for evening the teeth of saws for the use of carpenters and others, by means of which they can put their saws in order without incurring the loss of time and inconvenience of taking them to a person who makes a business of filing saws and putting them in order.

15 The invention consists in a saw-jointer composed of a metallic holder or frame made adjustable to receive and hold an ordinary triangular file and to adapt it for use on saws of different thicknesses, as hereinafter particularly described.

20 The ordinary method of jointing saws has been to draw a flat file over the cutting-edge of the saw by hand; but by that means it is impossible to set the cutting-edges of the teeth precisely at right angles to the plane of 25 the blade, and it also necessitates the providing a special file for jointing. These difficulties have been partially removed by a saw-jointer described in Letters Patent No. 277,364, in which a file is held in a carrier; but said carrier is not constructed to admit of adjustment either to different thicknesses of saw-blades nor to different sizes of files; and I do not claim that construction. By means of my invention these difficulties are obviated, as the 30 teeth are perfectly equalized in length, so that the cutting-edge of the saw presents a straight line, and the cutting-edge of each tooth is brought to a right angle with the plane of the saw, both of which conditions are necessary 35 to enable a saw to work perfectly; and in addition to this a further advantage obtained by my invention is that the triangular files which

have been worn out at their edges in their ordinary use in filing saws may be utilized for the purpose of jointing, as the flat sides 50 of the same generally remain intact and in good condition.

In the accompanying drawings, Figure 1 represents a side elevation of my saw-jointer; Fig. 2, a plan view of the same, and Fig. 3 is a transverse section on the line *xx*.

Similar letters of reference indicate the same parts in all the figures.

A is a cap-piece, and B B' two side pieces, which together form the holder or frame of 60 my saw-jointer and receive and hold an ordinary triangular file, C. The cap-piece A is made hollow or tubular to receive said file, and has two flanges, *a* and *a'*, one on each side, as shown. The two side pieces, B and 65 B', consist of two metal plates, the lower portions, *b* and *b'*, of which rest against the sides of the saw, and their upper portions, *c* and *c'*, are set at right angles thereto, and form flanges which fit to the flanges *a* and *a'* 70 of the cap-piece. The flanges *a* and *b* are riveted together, as shown at *d*, and the flange *a'* of the cap-piece is provided with a short slot, *f*, through which a set-screw, *g*, is passed, said screw entering the flange *b'* of the side 75 piece B', so that the space *h* between the two side pieces may be increased or diminished in order to properly fit the latter to saws of different thicknesses or sizes. The upper inner edges of the side pieces are slightly 80 rounded or cut away to allow for the spread of the teeth of the saw, while the lower inner surfaces of said side pieces fit snugly to the saw-blade. The lower edges of the file C rest upon the flanges *b* and *b'*, and said file is 85 clamped in position by means of a set-screw, *m*, which passes through the top of the cap-piece.

D represents a saw.

In using my improved saw-jointer the side 90 piece *b'* is adjusted to the thickness of the saw, so as to fit snugly to the blade, and the instrument is then passed to and fro with the file in contact with the teeth of the saw, which

are thereby brought to a uniform level throughout the entire length of the saw, and the cutting-edge of each tooth is brought to a right angle with the plane of the blade.

5 What I claim as my invention is—

In a saw-jointer, the combination of a hollow cap-piece, A, having flanges *a* and *a'*, two side pieces, B and B', having flanges *b* and *b'*, said

side piece B' being made adjustable, as described, and a file, C, clamped between said cap-piece and side pieces, substantially as shown and described.

BARNARD S. BOZARD.
